Specification for Design.

Patented Feb. 22, 1921.

Application filed February 16, 1920. Serial No. 359,185. Term of patent 7 years.

To all whom it may concern:

Be it known that I, CHARLES S. PRIZER, a citizen of the United States, residing at Somerville, in the county of Somerset and State of New Jersey, have invented a certain new, original, and ornamental Design for a Hot-Air Furnace, of which the following is a specification, reference being had to the accompanying drawing, forming part thereof.

The drawing is an elevation of a hot air furnace, showing my new design.

I claim:

The ornamental design for a hot air furnace, as shown.

In testimony whereof I affix my signature.

CHARLES S. PRIZER.
